UNITED STATES PATENT OFFICE.

FREDERICK J. SPIEGLER, OF CHICAGO, ILLINOIS.

SPOUT FOR CANS.

SPECIFICATION forming part of Letters Patent No. 720,854, dated February 17, 1903.

Application filed December 22, 1902. Serial No. 136,223. (No model.)

To all whom it may concern:

Be it known that I, FREDERICK J. SPIEGLER, a citizen of the United States, residing at Chicago, in the county of Cook and State of Illinois, have invented a new and useful Spout 5 for Cans, of which the following is a specification.

My invention relates to spouts for oil-cans and other vessels; and my primary object is 10 to provide a spout of simple construction and improved operation by means of which a vessel may be readily filled with proper apparatus for the purpose, but which cannot be readily filled without such apparatus.

15 A further object of the invention is to provide a spout of this character which may be readily closed securely for transportation purposes.

The invention is illustrated in its preferred form in the accompanying drawings, in which—

Figure 1 represents a broken sectional view of a can equipped with my improved device, the spout being in the closed position; and 25 Fig. 2, a similar view, the spout being in the open position.

The preferred construction is as follows:

A represents a can or vessel provided at a with a suitable opening; B, a combined neck 30 and valve-seat having soldered connection with the top of the can at the opening a; C, a cup-shaped member fitting within the member B and having screw connection therewith; C', a top for the member C, having 35 soldered connection therewith; D, a valve-stem connected with the top and bottom of the member C and bearing at its lower end a valve D', and E a spout passing through suitable perforations in the top and bottom of the 40 member C and having soldered connections at said perforations. As thus described, the member B has an annular flange at its lower portion, affording a valve-seat b, the upper surface of which is equipped with valve-leather b'. The member C has a bottom c provided with an air-vent c', and the top 45 member C' has an air-vent c''. The valve-stem D preferably passes centrally through the top C' and the bottom c of the member C and has soldered connections at the perforations 50 through which it passes. The valve D' is secured to the lower end of the valve-stem

in any suitable manner, usually by soldering or riveting, although the connection may be made by means of a nut, as shown. The upper surface of the valve is shown equipped with a valve-leather d, although in practice this may be omitted. The spout E has the lower end of its front or concave side stopping flush with the lower surface of the bottom c, 60 while the rear portion of the spout extends down into contact with the valve D', as shown at d'. Thus the lower portion of the spout has a cut-away portion or space d'', through which oil may pass when the valve is in the 65 depressed position. (Shown in Fig. 2.) When the valve is in the raised position corresponding with the open position of the spout, the spout is turned over the body of the can, as shown in Fig. 1, and when the valve is in the 70 depressed position corresponding with the open position of the spout the spout projects over one edge of the can, as shown in Fig. 2.

The manner of use will be readily understood. When the can is to be filled, the member C is turned downwardly to the position shown in Fig. 2, thereby depressing the valve below its seat and bringing the circumferential margin of the bottom c into firm contact with the valve-leather b'. The can may then 80 be filled by hanging it beneath the supply-tank, with the spigot of the supply-tank applied to the spout of the can. As the oil enters the can the air is allowed to vent freely, as is evident, while the oil is guided by the 85 lower portion of the spout, so that none of it will escape through the vent. When it is desired to pour out the oil, this may be done in the usual manner, assuming the valve to be in the position indicated in Fig. 2, air passing 90 freely in at the vents. In this position of the parts there is no possibility of the oil leaking through the thread joining the members B and C, inasmuch as the circumferential margin of the bottom c presses firmly 95 upon the valve-leather b'.

The spout E may be of any desired shape and cross-section, so that it will be necessary to apply the can to a tank equipped with a similarly-shaped spigot for the purpose of filling the can.

It may be stated that one use to which a can of this character is put by the oil-merchant is that of presenting it to his custom-

ers, whom he expects in return to purchase their oil from him. Usually the oil-merchant provides himself with a tank having a number of spigots or faucets, so that a number of cans can be filled at the same time, thereby removing the objection to the slowness of filling, which would prevent the use of the cans by a merchant not provided with the filling apparatus.

10 It will be noted that the passage through the spout E is entirely distinct from the chamber in the hollow member C, so that the oil will not enter the chamber C either in filling the can or pouring out the oil.

15 Changes in details of construction within the spirit of the invention may be made. Hence no undue limitation is to be understood from the foregoing detailed description, which has been given for clearness of understanding only.

What I regard as new, and desire to secure by Letters Patent, is—

1. The combination with a vessel having a threaded neck portion, of a hollow member provided with a vent-passage and threaded to work in said neck portion, a spout extending through said hollow member and having an open end beneath the same, and a valve carried by said hollow member and adapted

30 to move therewith, for the purpose set forth.

2. The combination of a vessel provided with a threaded neck portion and a valve-seat at the base thereof, of a hollow member threaded to work in said neck portion and having 35 vent-passages, a valve-stem connected with said member and equipped beneath said valve-seat with a valve, and a spout extending through said hollow member and having its rear portion projecting beneath the bottom thereof, for the purpose set forth.

3. The combination with a vessel having a neck portion equipped at its base with a valve-seat and provided with a thread, a member threaded to turn in said neck portion and having a peripheral surface at its base adapted to bear upon said valve-seat, a valve-stem projecting downwardly from said last-named member and equipped beneath said valve-seat with a valve, and a spout extending

50 through said member and moving therewith, for the purpose set forth.

4. In combination, a vessel equipped with

a neck portion having at its base a valve-seat, said neck portion being internally threaded, a hollow member threaded externally to work within said neck portion and provided at its bottom with a vent-perforation and at its upper portion with a vent-perforation, the peripheral portion of said bottom serving to bear upon said valve-seat in the open position of the device, a valve-stem carried by said hollow member, a valve beneath said valve-seat and connected with said stem, said valve serving to close the opening in the vessel when said hollow member is in its raised position, and a spout extending through said hollow member, for the purpose set forth.

5. The combination with a can, of a threaded neck portion B equipped at its lower end with an annular flange b, a hollow member C threaded to work within the member B, a washer confined between the peripheral portion of the bottom of the member C and the flange b, a valve-stem connected with said hollow member to be moved thereby, a valve connected with the lower extremity of said stem and lying beneath said flange b, and a spout extending through said hollow member and having liquid-tight connections therewith, said spout having at the base of its rear portion a downward extension b' extending below the bottom of the member C, for the purpose set forth.

6. The combination of a can provided at its top with a perforation, of a neck portion applied to the can-top at its opening and having an inturned annular flange, a hollow member working within said neck portion and having threaded connection therewith and provided with vent-openings, a valve-stem extending through the top and bottom of said hollow member and projecting beneath said annular flange, a valve connected with the lower end of said stem, and a spout extending through perforations in said hollow member and having liquid-tight connections therewith, said spout having a downward extension at the rear portion of its base, for the purpose set forth.

FREDERICK J. SPIEGLER.
